UNITED STATES PATENT OFFICE.

ALBERT C. CALKINS, OF LOS ANGELES, CALIFORNIA, ASSIGNOR TO
FREDERICK W. BRAUN, OF SAME PLACE.

ORE-SAMPLING MACHINE.

SPECIFICATION forming part of Letters Patent No. 682,528, dated September 10, 1901.

Application filed November 19, 1900. Serial No. 36,990. (No model.)

To all whom it may concern:

Be it known that I, ALBERT C. CALKINS, of Los Angeles, in the county of Los Angeles and State of California, have invented a new and 5 useful Improvement in Ore-Sampling Machines, of which the following is a specification.

My invention is in the nature of an improved sampling-machine designed more especially for the use of assayers for rapidly and efficiently mixing and subdividing a quantity of pulverized ore, of which a representative sample may be desired, but which machine is also applicable for mixing and 15 sampling or subdividing any kind of material, as is frequently required in the drug trade.

My invention consists in the peculiar construction and arrangement of the various 20 parts of such sampling-machine, as will be hereinafter fully described with reference to the drawings, in which—

Figure 1 is a side elevation of the entire machine with the mixing-buckets and actuating-gears in section. Fig. 2 is a rear elevation. Fig. 3 is a plan view of the upper bucket; Fig. 4, a plan of the lower bucket, and Fig. 5 is a detail view of the supporting-bracket for the buckets and gears.

The device consists of hopper A and two buckets B C. The buckets are under the hopper, and one of the buckets, C, is under the other, B. These buckets have radial partitions, forming four divisions each. (See 35 Figs. 3 and 4.) Two of these divisions in each bucket are closed at the bottom and two are open. The open pockets in each bucket are directly opposite each other, as are the closed pockets directly opposite each other. The 40 upper and lower buckets are substantially identical in size and arrangement of the divisions and openings, the only difference between them being the provision made for fastening the buckets one over the other.

The upper one, B, has a central cone b, that distributes the stream of ore, and it sits on and is fastened to a bevel-pinion b', which rotates it in one direction, while the other bucket C is suspended under its mate from 45 another bevel-pinion c' and is rotated by means of an intermediate bevel-gear d in an

opposite direction. The upper bevel-gear b' is formed with a pendent peripheral flange b², that covers the gears and excludes dust, and a central closed hub b³, while the lower 55 bucket has a rigidly-attached spider-frame c², which is screwed to the lower bevel-gear. The intermediate gear d rotates both buckets and is actuated by a crank E on a shaft passing through a frame-coupling F and the gear-bracket D. The hopper which discharges into the top bucket receives four jolts or shakes to each revolution of the crank by means of a square cam e on the crank-shaft bumping a rod G, connected to the hopper A. The 60 material being sampled is gradually jolted out of the hopper into the upper bucket on the apex of the cone, thence half of what is discharged into the upper bucket passes into the lower bucket. This half is again divided 65 into half by the lower bucket. One quarter of the amount originally put into the machine is discharged from the lower bucket onto the floor or into a receptacle provided for the purpose and another quarter remains in the 70 lower bucket. The four pockets in each bucket divide the ore into quarters, and the two diagonally opposite pockets being open allow the two diagonally opposite quarterings to pass through into the lower bucket, 75 where the same office is performed. Thus the two diagonally opposite quarterings are held up and the other two quarterings, which are diagonally opposite to each other, are passed through. Thus it may be readily seen 80 that this machine not only thoroughly mixes the charges by a centrifugal action, but accurately quarters it.

The machine is very simple in construction. The buckets and hopper are of sheet metal, 90 and the frame consists of a gear-bracket D, one end of which, F, unites two pieces of iron pipe S S', which form the standard. The bottom of the lower pipe fits into a floor-flange, which forms the base or footing of the machine. The hopper is pivoted to the top of the upper pipe, the four-phase cam e is cast to the crank, and the crank is fastened to the shaft of the intermediate gear, which shaft passes longitudinally through a hole or bearing in the gear-bracket D. An extended flange d' is cast on the gear-bracket D, which 95 100

prevents the centrifugal force from scattering the material leaving the upper bucket and insures that it falls into the lower bucket. The upper edge of this shield extends upward 5 and around the bottom of the upper bucket, and the lower edge of the shield extends downward within the top of the lower bucket. The central hub of the gear-bracket has a screw s , that holds the vertical shaft s' , that 10 forms the axis of the upper and lower bevel gears.

The shake-rod G is of steel and has an eye at its upper end connecting with the hopper, and the lower end makes a right-angle bend 15 around the cam (see Fig. 2) and fastens to an adjusting-pin p or stud by means of an eye and cotter-pin. The lug l , which holds the pin, is slotted vertically, so that the pin carrying the lower end of the shake-rod may 20 be slipped up or down, thus bringing the bent end of the shake-rod as near to or far from the cam as is necessary to give the degree of shake desired. The lower end and angle bend of the shake-rod are tempered to 25 prevent the rod from bending and thus escaping the cam.

Having thus described my invention, what I claim as new, and desire to secure by Letters Patent, is—

30 1. In a mixing and subdividing apparatus, the combination of a bucket having a series of compartments disposed around the center a portion of which are open at the bottom, and gears for rotating the bucket located 35 in the vertical center of the bucket and inside the circle of the discharge-openings substantially as described.

2. In a mixing and subdividing apparatus, the combination of two buckets arranged one 40 above the other and having a series of compartments disposed in a circle about the center a portion of which are open at the bottom, and double-acting gears for rotating the buckets in opposite directions, said gears being located centrally inside the circle of the 45 discharge-openings and between the buckets substantially as described.

3. A mixing and subdividing apparatus comprising two buckets or chambers having 50 radial partitions forming compartments a part of which are open at the bottom and a part closed, the buckets being arranged one above the other and discharging from one into the other, and means for rotating the buckets in opposite direction substantially 55 as described.

4. A mixing and subdividing apparatus, comprising two buckets having radial partitions forming chambers with openings at the 60 bottom, and a double-acting gear arranged between and in central relation to the two buckets to rotate them in opposite directions substantially as described.

5. A mixing and subdividing apparatus 65 comprising a standard made in two sections, a coupling connecting the same and formed

with a supporting-bracket frame, double-acting gears arranged in said frame, and two mixing and dividing buckets arranged one above and the other below said gears and rotating in opposite directions substantially as 70 described.

6. In a mixing and subdividing apparatus, the combination with an upper and lower bucket having discharge-openings at the bottom, double-acting gears arranged between them for rotating them in opposite directions and a stationary projecting flange extending above and outside the lower edge of the upper bucket, and arranged inside the outer 80 wall of the lower bucket, substantially as described.

7. In a mixing and subdividing apparatus, the combination of two reversely-rotating buckets having openings in the bottom, reversely-operating gears for the same, an oscillating hopper arranged above the buckets, a shaft for rotating the gears, and a cam and rod for imparting motion from the shaft to the oscillating hopper substantially as described.

8. In a mixing and subdividing apparatus, the combination of a frame D supported at one side and having a central vertical shaft s' , in combination with a bevel-gear b' with closed hub b^3 and pendent covering-flange b^2 , 95 and a surmounting bucket having radial partitions and bottom, openings and a driving gear-wheel housed and covered by the flange b^2 substantially as described.

9. In a mixing and subdividing apparatus, 100 the combination of a frame D supported at one side and having a central vertical shaft s' , a bucket having a flanged gear-wheel attached to its lower side and mounted on the upper end of the shaft, a second bucket with 105 gear-wheel attached to the upper part of the same and sustained upon the lower end of said shaft, and an intermediate driving-gear for rotating the two buckets in opposite directions substantially as described.

10. In a mixing and subdividing apparatus, the combination with a revolving bucket, and its gears and supporting-frame; of a hollow vertical standard with coupling F a horizontal drive-shaft passing through said coupling 115 and having a cam, a rod operated upon by said cam, and an oscillating hopper connected to the rod substantially as described.

11. In a mixing and subdividing apparatus, the combination with the rotary buckets, and the crank-shaft having cam e ; of the coupling-section F having stud l with slot in its end, the pin p , the bent rod G jointed to the pin and extending horizontally past the cam to be acted upon by the same, and thence 125 extended upwardly; and an oscillating hopper connected to the upper end of said rod, substantially as described.
